[57] CLAIM

The ornamental design for a slide fastener chain, substantially as shown and described.

DESCRIPTION

FIG. 1 is a top plan view of a slide fastener chain showing our new design;

FIG. 2 is a front elevational view thereof;

FIG. 3 is a rear elevational view thereof;

FIG. 4 is a side elevational view thereof;

FIG. 5 is an enlarged fragmentary front elevational view thereof.

FIG. 6 is an enlarged side elevational view of FIG. 5; and

FIG. 7 is an enlarged top plan view thereof.

The characteristic feature of our design resides in the clear fastener elements, each displaying the appearance of tiny particles embedded within.
